UNITED STATES PATENT OFFICE.

CARL MACK, OF NEW YORK, N. Y., ASSIGNOR, BY MESNE ASSIGNMENTS, TO SAMUEL BONAT AND HARRY BONAT, CONSTITUTING THE FIRM OF SAMUEL BONAT & BRO., OF NEW YORK, N. Y.

HAIR WINDER.

Application filed June 29, 1926. Serial No. 119,359.

This invention relates to hair winders and has particular reference to a device for winding long hair whereby it can be more tightly and uniformly wound than has been possible by the methods heretofore employed in the hair dressing process commonly known as permanent waving. In the present methods of hair winding, the hair is wound by hand and is held in position by the fingers during the winding operation, so that the uniformity and degree of tightness of the winding is dependent solely upon the skill of the operator, and usually takes considerable time when done carefully. Furthermore, in winding long hair by hand it must be continuously combed to keep it from snarling, which considerably increases the work of properly winding the hair.

Among the important advantages of the hair winder of this invention is that by means of this device the winding of long hair may be done rapidly, uniformly and without continual combing, by a relatively unskilled operator since the device eliminates all those separate hand operations which are employed by a skillful hair dresser, and accomplishes the same results in an improved manner. Furthermore, the proper degree of tension as maintained along the entire length of the lock of hair during the winding operation, so that the proper degree of tightness is uniformly maintained for each turn of the lock of hair around the curling rod. This advantage is effected by a plurality of spaced friction clips which hold the lock of hair against the body of the winder so that the proper uniform tension of the hair is imparted as it is drawn from beneath these successive clips in being wound upon the curling rod. A certain friction between the winder and the curling rod as the latter is held in the winder, aids in maintaining the proper tension of the hair as it passes from the winder to the curling rod.

For a better understanding of the invention, reference may be had to the accompanying drawings, in which

Figure 1 is a front elevation of the hair winder of this invention, showing the method of holding the hair while it is being wound upon the curling rod;

Fig. 2 is a side view of the device, show-

ing the hair holding clips in phantom to illustrate their disengaged position;

Fig. 3 is a rear view shown in partial section; and

Fig. 4 is a view of working end of the device.

Referring to Fig. 1 of the drawings, numeral 1 designates the body of the hair winder, which is provided with a plurality of hinged clips 2, 2^a and 2^b. These clips are preferably U-shaped, one arm being disposed so as to extend transversely across the face of body 1, whereas the other arm projects through the body 1 and is encircled by a coiled spring 3, which is disposed thereon between the head of an attached screw 4 and a shoulder formed by the recess in body 1. Transverse grooves 5 across the side of body 1 hold these clips 2, 2^a and 2^b in the disengaged position shown in phantom in Figs. 2 and 4 when screw head 4 is pushed against spring 3, thereby causing a sort of cam action between the edges of grooves 5 and clips 2, 2^a and 2^b so that the clips slip into the grooves when the pressure upon 4 is removed.

Curling rod 6, provided with a hair receiving slot 6^a, is held in body 1 by a friction block 7, which is constrained against rod 6 by springs 8 disposed between it and the enclosing frame 12, which is attached to body 1 by means of screws 13. A screw 9 serves as a guide for block 7.

A plunger 10 is provided in the end of the device for the purpose of pressing the hair against curling rod 6, and is movable in and out of the body 1 against the tension of spring 11, which is mounted in frame 12. The edge of body 1 over which the hair passes, is preferably rounded as shown in Figs. 1 and 2, and a pin 14 is fixed near this edge for the purpose of guiding the hair as it is drawn from body 1 during the winding operation.

In operating the new hair winder, the lock of hair, after being previously prepared in the usual manner, is passed through slot 6^a in curling rod 6 between curling rod 6 and plunger 10, and is then laid along the face of body 1 under the clips 2, 2^a and 2^b, which are in the disengaged position shown in phantom in Figs. 1 and 4, and which are then successively pressed downwardly to en-

gage and thus hold the lock of hair upon the face of body 1 with the same tension at which it was drawn thereon.

If only a portion of the lock of hair is intended to be waved, the body part of the winder will serve primarily as a holder for that part of the lock of hair which is not to be waved, thus keeping it from snarling as the winder is twisted by the operator and thereby eliminating the combing of that part during the winding of the remainder of the lock of hair.

In dressing the entire length of long hair, however, the winder is moved along curling rod 6 with a spiral motion in the usual manner, thereby winding the hair around the rod 6 and drawing it at the proper tension from beneath clips 2, 2^a and 2^b so as to wind it tightly and uniformly upon curling rod 6, at the same time pressing and smoothing it against the latter by means of plunger 10. Until the end of the lock of hair is drawn from under the last clip 2, these clips keep the hair smooth and free from tangles and thus eliminate continual combing, while the friction between body 1 and rod 6, caused by friction block 7, aids in keeping the lock of hair taut when it leaves the last clip 2. Before the end of the lock of hair leaves the last clip 2, it is secured to curling rod 6 in the usual manner.

The new hair winder is especially adapted for facilitating the dressing of long hair, either along its entire length or only a portion thereof, and is equally useful for dressing short or bobbed hair since it will receive hair of all lengths and may be readily manipulated for any length of hair. However,

such modifications as are deemed necessary may be made to any desired degree within 40 the scope of the appended claims.

I claim:

1. In a hair winder, the combination of an elongated member adapted to be moved along a curling rod, friction means on said member for engaging the rod, a plurality of spring clips spaced along said member for holding the hair tautly thereon, and means for releasing the pressure of said clips.

2. In a hair winder, the combination of an elongated member adapted to be moved relatively to a curling rod, friction means on said member for slidably holding the curling rod, a plurality of transverse clips spaced along said member for jointly clamping a lock of hair to said member, and means on said member cooperating with the curling rod to smooth the lock of hair thereon during the winding operation.

3. In a hair winder, the combination of a curling rod, a member adapted to cooperate with said rod, and a plurality of clips for holding the hair on the member, said clips comprising bars disposed transversely of said member and spring-constrained against the latter.

4. In a hair winder, the combination of a curling rod, an elongated member for holding a lock of hair, a plurality of clips spaced along said member for clamping the hair thereto, said clips comprising transverse bars pivotally mounted on said member, and friction means for holding said rod and said member together.

CARL MACK.
